UNITED STATES PATENT OFFICE.

WILLIAM M. LUTHER, OF SAN FRANCISCO, CALIFORNIA.

PARING-MACHINE FEEDER.

1,217,872.

Specification of Letters Patent. Patented Feb. 27, 1917.

Application filed October 20, 1914. Serial No. 867,651.

To all whom it may concern:

Be it known that I, WILLIAM M. LUTHER, a citizen of the United States, residing in the city and county of San Francisco, State 5 of California, (whose post-office address is 1242 Taylor street,) have invented new and useful Improvements in Paring-Machine Feeders, of which the following is a specification.

10 This invention relates to improvements in feeding machines, and more particularly to means for feeding fruit and the like, to paring and coring machines. Attention is directed to my copending application in this 15 same class, bearing Serial #860,453, and filed September 5, 1914.

Machines for peeling, coring and paring fruit and vegetables, for canning, preserving and other processes, have reached a very 20 satisfactory degree of development, so far as their particular function is concerned; but within my knowledge there has not been produced a satisfactory means for feeding a multiple of such machines. It is still the 25 practice for the operator to feed the spindles of the paring machine directly by hand. This hand method of feeding involves considerable delay, since the operator loses that 30 interval of time, during which the spindle is occupied by the fruit, undergoing the process performed by the machine, and must wait for the spindle to be freed, before he can place thereon another unit, and to make up for the interval of delay must act with a 35 speed not conducive to accuracy or economy in handling the fruit.

Among the objects of this invention are the correction of the above disadvantages, by producing a feeding mechanism, that is 40 applicable to the standardized, peeling, paring and coring machines in general use at the present time;

That will feed a single machine, or a bank 45 or multiple of machines; limited only by the efficiency of the operator;

That is so timed that an interval of inaction is permitted in the feeder, during 50 which the operator can place the fruit in the feeder with judgment, without loss of efficiency in producing results;

That is general in its application, easily and quickly installed, and adjustable to varying conditions;

That is simple and positive in action safe

to operate, and that will not bruise or mutilate the fruit. 55

Other objects and advantages will appear as the description progresses. In the drawing accompanying and forming part of the present specification, to which like reference characters have been applied, a desirable 60 form of putting this invention into practice is shown. I do not wish to be understood as confining this invention to the disclosures made in said drawing and description, as 65 many variations may be introduced, within the spirit of this invention, as defined in the claims succeeding the said description.

In the drawings:

Figure 1 is a diagrammatic side elevation 70 of a conventional type of peeling and coring machine for apples, pears and other such fruit; some of the minor details of the machine having been omitted, as not germane to this invention; showing a feeding mechanism constructed and combined therewith in accordance with this invention, showing in dotted lines, the gripper mechanism at rest during the dwell interval of the actuating cycle. 75

Fig. 2 is a plan view from above of a multiple of four such paring machines,—broken away in diagrammatic detail, better to disclose the feeding mechanism,—showing a pair of double feeders serving the four 80 spindles of the paring machines, the feeders being synchronized so that one feeder is in the charging position, while the other is in the serving position, so arranged that one operator is enabled to charge the feeders 85 for the four machines. 90

In detail the construction illustrated in the drawing, includes the paring machines, comprising a main frame 1 having the bases 2, adapted to be secured to a bench or bed-plate. These machines have a main driven shaft 3 journaled in the frame 1, and actuated by the gear wheel 4 fixed thereon. The pinion 5 fixed on the opposite end of the shaft 3, or on a shaft geared to shaft 3, actuates the pinion 6 enmeshed therewith, and fixed upon the sleeve 7 journaled within the brackets 8. The collapsible spring chuck 9 is fixed in the end of the sleeve 7, and may consist of three spring jaws having barbed 105 heads, adapted to be forced into the fruit X, to firmly engage the fruit, for rotation.

A paring knife is mounted on the arm 10,

actuated by a cam driven by the worm gearing 11, in turn driven by the shaft 12 having the pinion 13 fixed thereon, enmeshed with the gear 14 mounted on a counter shaft 15 in the main frame, and enmeshed with a driving pinion 16, fixed on the driven shaft 3. The cam—not shown—causes the peeling blade to follow the contour of the fruit being revolved by the chuck 9, causing the blade to remove a thin peeling from the whole surface of the fruit. After the peeling operation, the revolving frame of which the bracket 8 is a part, moves forward to a position opposite the coring blade, that is 15 semicircular in cross section, conforming to the outline of the chuck 9. The coring blade advances cutting out the core of the fruit, that is left on the chuck while the fruit is carried backward on the coring blade during 20 its return stroke, stripped off and delivered to a hopper beneath the bench. The core is removed by the plunger 17 working within the sleeve 7, and pushed forward at the proper time in the revolution of the bracket 25 8, to strip the core off of the chuck 9.

The above outline description of the coring machine, includes its principal functions and the general means adopted for their accomplishments. These means will 30 vary in different types of machines, but are common to most of them, and no claim for a paring machine *per se* is made herein.

The main driving gear consists of the shaft 18, journaled in the bearings 19 and 35 20 on the bench. The driving gears 4 on the respective paring machines, are enmeshed with the driving gears 21 fixed on the shaft 18, one gear 21 serving to rotate the gears 4—4 enmeshed on opposite sides 40 thereof. A similar driving mechanism is located between the adjacent pair of paring machines, each of the shafts 18 being provided with the sprocket gears 22—22 fixed thereon, and connected by the endless 45 sprocket chain 23.

The feeding mechanism includes the bevel pinion 24, fixed on the end of the shaft 18, and enmeshed with the bevel gear 25 mounted on the stud shaft 26, fixed in the bracket 50 27, attached to the bench or bedplate of the machine. The gear 25 is provided with the crank pin 28, extending from the side of the gear wheel. The connecting rod 29 is journaled on the pin 28. The revolution of the 55 bevel gear 25 causes an oscillating reciprocation of the connecting rod 29. The connecting rod 29 passes through and is slidably guided in the tubular extension 31, the pin 32 passing through the connecting rod and 60 engaging the slot 33 through the tubular extension.

The opposite end of the extension 31 is provided with the T head 34 engaging the cross shaft 35 of the gripper carriage. The 65 compression spring 36 is inclosed within

the bore of the tubular extension 31 and expands against the ends of the connecting rod at one end, and against the end 37 of the bore of the extension 31, at its other end. The reciprocations of the connecting rod 70 29, actuated by the crank pin 28, causes the reciprocation of the shaft 35 of the carriage. To cause a dwell interval during the revolution of the gear 25 between the points A—B, see Fig. 1, the arc of movement of the gripper is less than the stroke of the connecting rod 29; this difference in distance being compensated for by the compression of the spring 36, during the period in the cycle that the crank pin is passing from A to B, or 80 any other chosen degree of the revolution.

The gripper carriage includes the base brackets 38—38 securely fixed on the table X' forming the bedplate. The cross shafts 40 and 41 have shouldered ends journaled in these brackets 38. The supporting levers 42—42 have their nether ends fixed on the shaft 41 and their opposite ends pivoted on the shaft 43. The arm 44 is keyed to the shaft 43 from which it extends outwardly 90 and is pivoted at 45 to the control link 46 fixed on the shaft 40 pivoted in the brackets 38. The supporting levers 42, the arm 44, and the control link 46 mounted between the brackets 38, constitute a toggle like mechanism or carriage to control the evolutions of the gripper in receiving the fruit and feeding it to the paring machine. The hollow stem 47 of the gripper is adjustably fixed within the clamp 48 that is rigidly fixed on the shaft 43, and is held in the desired adjustment by the pinch of the clamp. The stem 47, extends upward and is capped by a concave head 49 rigidly fixed thereon, and provided with a central sharpened spike 50, 100 adapted to engage and center the fruit impaled thereon.

The gripper includes a spider having the central hub 51, fixed on the stem 47 by any suitable means. This spider has the arms 110 53, preferably three in number, extending outwardly therefrom on radial lines and terminating in the divided heads, between the sides 54 of which the gripper fingers 55 are pivoted on the pins 56 extending through 115 the heads. These gripper fingers have an inward extension 57, engaging the annular groove 58, in the collar 59, slidably surrounding the stem 47. The plunger 60 is guided centrally within the stem 47 from 120 which it protrudes at the bottom, and has a cross pin fixed in the upper end and extending through a slot in the stem 47 and engaging the collar 59. A compression spring confined within the hollow stem, expands between the head of the plunger 60 and the underside of the head 49, to maintain the normal protrusion of the plunger 60 beyond the lower end of the stem 47.

Starting from the position shown in Fig. 130

1 the back stroke of the crank pin 28, operating through the connecting rod and intermediate mechanisms forces the shaft 35 rearward, carrying the gripper carriage 5 backward from the feeding to the charging position, shown in dotted lines Fig. 1. The center of the arc of the movement of the gripper is struck from the axis of the shaft 41. This movement however, must be modified to cause the gripper to move in a line tangential to this arc in approaching and receding from the spindle chuck 9. This tangential movement is accomplished by centering the control mechanism of the gripper 15 on the shaft 40 that is spaced backward from the shaft 41. The substantially parallel movement of the supporting levers 42 and the control links 46 tend to hold the gripper on a substantially horizontal plane, 20 during the first and last portions of the stroke of the crank pin, for the purpose previously described; the control link 46 pivoted to the arm 44, that is rigidly fixed to the shaft 43 upon which the gripper is 25 also rigidly fixed, permits a wrist movement at the pivot 45 that compensates for the differential movement between the stroke of the crank pin and the stroke of the gripper. The ratio of leverage in the various 30 mechanisms forming the gripper control may be varied to meet the feeding conditions of the various types of paring machines.

When the stem 47 assumes the vertical position during the A—B cycle previously 35 described, see dotted lines Fig. 1, the end of the plunger 60 abuts the plane of the table X' within which a soft bumper such as 64 may be inserted to lessen the shock. The impact of the plunger 60 with the bumper 40 64, forces the plunger upward against the tension of the spring, elevating the collar 59, forcing the extensions 57 upward and the fingers 55 outward. This action presents the gripper with the fingers open in 45 the vertical position, which condition is maintained during the dwell cycle A—B, during which period the operator selects the apples or other fruit and impales their bloom ends on the spikes 50.

50 The paring machines are preferably arranged in banks of four all driven at the same speed. The bank of four machines is again preferably divided into couples. The feeding mechanism is arranged to feed two 55 machines and is also arranged in couples and driven at the same rate of speed in synchronism with the machines that they are serving; and preferably so timed that one couplet of the feeders is dwelling in the 60 A—B cycle, while the other feeder is serving the other couplet of paring machines. This arrangement and synchronism of the various machines meets the capacity of the average operator, and divides his time in such a 65 manner, that the highest efficiency of ma-

chine and operator is attained. During the A—B cycle the operator chooses from the pile before him two apples or other fruit, one in each hand with bloom ends downward. These he impales upon the spikes 50, of the 70 couplet of grippers presented vertically before him with the gripper fingers open. During this action of the operator, the companion set of grippers have come to rest in their A—B cycle, and the operation is repeated alternately by each couplet. The speed of the machines is regulated according to the dexterity of the operator. This arrangement described is not arbitrary, and it is obvious that it may be varied or modified to suit conditions. 80

The stroke of the crank pin 28 after the A—B cycle reverses the action of the control mechanism previously described, and carries the gripper upward toward the horizontal position illustrated in Fig. 1; as the plunger leaves the stop 64 the expansion of the gripper spring forces the plunger and collar downward, carrying with it the extensions 57, which carry the gripper fingers 90 55 inward toward the fruit impaled upon the spike 50, which is seized with a grip regulated by the tension of the gripper spring. Three gripper fingers are preferred, as being sufficient in number, and being unequal in number, tend better to center the fruit within the gripper, for presentation of the stem end to the chucks 9, upon which the fruit is forced by the continued 95 forward movement of the crank pin 28, connected to the gripper control mechanism. 100

The gripper can be adjusted to receive and carry different sizes of fruit by adjusting the stem 47 within the clamp 48, the further the stem 47 protrudes beyond the clamp 105 the higher the plunger will be forced upward, opening the gripper fingers in proportion, and vice versa.

Having thus described this invention what I claim and desire to secure by Letters 110 Patent is:

1. A feeding mechanism including a bracket; a supporting lever pivoted in said bracket; a gripper pivoted on said supporting lever, a control lever pivoted to said 115 gripper, and pivoted to said bracket on a center spaced from the pivotal center of said supporting lever; and means for swinging said supporting lever.

2. A feeding mechanism including a 120 bracket; a supporting lever pivoted in said bracket; a gripper pivoted on said supporting lever, and having an arm extending outward therefrom; a control link pivoted to said arm and to said bracket; and means for 125 swinging said supporting lever.

3. A feeding mechanism including a bracket; a supporting lever pivoted in said bracket; a gripper pivoted on said supporting lever, and having an arm extending out- 130

ward therefrom; a control link pivoted to said arm, and pivoted to said bracket on a center spaced from the pivotal center of said supporting lever; and means for swinging 5 said supporting lever.

4. In a feeding mechanism for fruit par-
ing machines, a gripper for the fruit, a piv-
oted lever attached to and supporting said
gripper, a reciprocating mechanism at-
tached to said lever, and control mechanism
also attached to said gripper for holding
the gripper in a substantially horizontal po-
sition during a portion of its movement. 10

5. In a feeding mechanism for fruit par-
ing machines, a gripper for the fruit, a piv-
oted lever attached to and supporting said
gripper, a reciprocating mechanism at-
tached to said lever, and control mechanism
also attached to said gripper, means for
20 causing the gripper to swing into a vertical
position, means for opening the gripper

while in vertical position and during the
dwell of said reciprocating mechanism, and
means for holding the gripper in a substan-
tially horizontal position during a portion 25
of its movement.

6. A feeding mechanism including a
bracket; a supporting lever pivoted in said
bracket; a gripper pivoted on said support-
ing lever; a control link pivoted to said 30
gripper and pivoted to said bracket on a
center spaced from the pivotal center of said
supporting lever; a reciprocating connect-
ing rod engaging said supporting lever and
a resilient member interposed in said con- 35
necting rod.

In testimony whereof, I have hereunto set
my hand this 15th day of October 1914.

WILLIAM M. LUTHER.
